UNITED STATES PATENT OFFICE.

JAMES W. DENNIS, OF CINCINNATI, OHIO, ASSIGNOR TO CLARA E. DENNIS,
OF SAME PLACE.

ELECTRO-MEDICAL APPLIANCE.

SPECIFICATION forming part of Letters Patent No. 285,977, dated October 2, 1883.
Application filed May 5, 1883. (No model.)

To all whom it may concern:

Be it known that I, JAMES W. DENNIS, a citizen of the United States, residing at Cincinnati, Hamilton county, Ohio, have invented 5 new and useful Improvements in Electro-Medical Appliances, of which the following is a specification.

My invention relates to appliances for the medical use of electricity, being intended to 10 provide a means of applying the current locally with convenience and certainty, according to the particular needs of the patient, and adapted to the particular contour of the part under treatment.

15 To this end my invention consists, primarily, in a cap or holder, of insulating material, adapted to the contour of the particular part or feature under treatment, and to be retained thereon either by its fit upon such part or feature or its relation to surrounding parts, and by such fit to hold a suitably-formed pole- 20 plate of conducting material upon or in electrical connection with the affected part, whereby the removal and reapplication of the transmitting-pole can be effected with convenience 25 by the patient, and retained when in position, leaving the hands free to manipulate the battery or connections.

It also consists in a particular form of holder, adapted in the present case to a tooth or similar part, and also in a switch device or wire-holder designed to be used in connection with the pole-holder above referred to, all as hereinafter more fully described.

35 Forms of apparatus embodying and illustrating the principle of my invention are shown in the accompanying drawings, in which—

Figure 1 is a perspective view of a double holder adapted for application to a tooth, to 40 the nose, or similar part. Figs. 2 and 3 are cross-sections of the same in position upon a tooth; and Fig. 4 is a view, partly sectional, of the switch device.

The parts herein described are indicated by 45 letters of reference in the drawings.

In carrying out my invention I employ a small plate, *a*, preferably of platinum, formed to the size and contour of the affected part as nearly as circumstances require, and embed

the same in a matrix or holder, preferably 50 formed of vulcanized rubber, also adapted in form to the contour of the part or surrounding parts. In the case shown the holder consists of two parts, *A A'*, formed at corresponding surfaces to the contour of the teeth, and 55 held by a short spring, *b*, either of the same or different material, the whole forming a clamp which may be slipped over and upon the tooth *C* and press against it from opposite sides. The pole-plates *a a* occupy a portion 60 of the interior surfaces of the clamp, and are provided with battery-wires *c*, extending through the backing-pieces, and provided with suitable insulating covering.

In use the surface of the plate is covered 65 with a piece of cloth, sponge, or punk, moistened with saline or slightly-acidulated water, which forms a conducting medium between the plate and the part to which it is to be applied.

70 It will be obvious, without a detailed description, that the wires *c c* may be used either attached to the same pole of the battery, the other pole being held in the hand or applied to some contiguous part; or these may be attached to opposite poles of the battery, thus 75 passing the current directly through the part, as indicated by the dotted arrow in Fig. 2. Either of the pole-plates may be insulated at will by interposing a piece of rubber sheet, *d*, 80 as shown in Fig. 3.

The spring *b* may be formed of steel or other suitable metal, as it is insulated by the pole-holders *A A'* from the electrical conductors.

85 It will be also obvious that a holder or clamp, substantially similar to that exhibited, may be used with equal advantage upon the nasal bridge, and, indeed, with all parts where the clamp form may be employed; also, that the backing may be made of other substances— 90 such as wood, glass, celluloid, and other non-conducting substances, and even of dental gum or impression wax—the object being to thoroughly insulate the plate *a* from all possibility of contact with other parts than that 95 directly under treatment, and at the same time to insure its application at required intervals to the same locality.

The use of the appliance is facilitated by employing the device B, (shown in Fig. 4,) which consists of two conducting-bars, *e e*, provided with insulating-coverings, and held side by side by rubber bands *ff* or otherwise. The bars project from their insulating-coverings below, where they are provided with binding-screws *gg*, and suitable perforations for making the battery-wire connections, and also with a switch-bar, *h*, pivoted upon one of the bars *e e*, and swinging over upon and electrically engaging the other. Supposing the wires *c' c'* to be connected with opposite poles of the battery, the switch *h* may be used to short-circuit the current pending the proper adjustment of the other parts. The upper ends of the bars *e e* are recessed to admit the connection of the wires *c c* by insertion of their free ends as plugs into the recesses; or, as a preferred construction, the bars *e e* are simply tubes, into which ordinary binding-posts are inserted as plugs at the lower ends, and the connection made, as before described, at the upper ends.

The device may also be used as a handle to support the pole-plate holders (where the nature of the use does not admit of a self-sustaining device, as in clamp form) by making the conductors *c c* of wires stiff enough to sustain the holders from the handle in the desired position.

I claim as my invention and desire to secure by Letters Patent—

1. A holder or pole-piece for the medical application of the electric current to the human body, consisting substantially of a metallic conducting-plate held upon or embedded in the surface of a backing-piece of vulcanized rubber or other insulating material adapted to the contour of the feature or part under treatment, and held in place by fitting upon the said or adjacent parts, and provided with insulated battery-connections, substantially as set forth. 35

2. In an appliance of the character described, a holder or pole-piece consisting of two parts, 40 each provided with a conducting-plate, and the two united by an insulated spring-connection, adapted to be used as a clamp to retain the plates against opposite sides of a tooth or other feature or part of the body, substantially as 45 specified.

3. In an appliance of the character described, a switch-handle consisting of two insulated tubes or bars, with provision at both ends for connecting electrical conductors, and a switch 50 for short-circuiting the electric current at will, substantially as specified.

In testimony whereof I have hereunto set my hand in the presence of two subscribing witnesses.

JAMES W. DENNIS.
